UNITED STATES PATENT OFFICE

OTTO E. SZEKELY, OF HOLLAND, MICHIGAN

DRIVING MECHANISM FOR COMBINED WASHERS AND WRINGERS

Application filed May 2, 1927, Serial No. 188,145. Renewed April 17, 1931.

This invention relates to driving mechanism for combined washers and wringers and it particularly relates to driving mechanism for washers and wringers which is adapted 5 to be operated by an electric motor.

The object of the invention is to provide a new and practical driving mechanism for a washing machine and a wringer.

Another object thereof is to provide a 10 driving mechanism in which slight variations and adjustments of the motor can be made relative to the driving mechanism.

Another object thereof is to provide improved means which is simple and efficient 15 for operating the impeller and wringer.

Another object thereof is to provide a rigid and direct drive for the impeller and wringer.

Another object thereof is to provide a 20 simple clutch arrangement whereby the wringer or washing machine may be intermittently operated.

Another object thereof is to provide a 25 washing machine having a frame or support which can be readily disconnected and assembled to allow a greater number of washing machines to be loaded into a normal freight car.

Other objects and advantages will herein- 30 after appear.

Fig. 1 is a perspective view of the washing machine and with the wringer attached.

Fig. 2 is perspective view of the washing 35 machine with the wringer and support detached.

Fig. 3 is a transverse section taken diagonally across the center of the machine showing the driving and operating mechanism.

Fig. 4 is a bottom plan view.

Fig. 5 is a detail sectional view taken on the line 5-5 of Fig. 4.

Fig. 6 is a detail sectional view taken longitudinally through the standard and gear casing.

Fig. 7 is an elevation of the motor and its support.

Fig. 8 is a detail plan view showing some of the mechanism in the gear casing.

Fig. 9 is a detail view of the clutch head casing.

Fig. 10 is a detail of the wringer locking device.

The invention comprises in general a tub 1 mounted on a frame 2, a wringer 3, and a motor 4 for driving the mechanism which 55 operates the washing machine and wringer.

The tub 1 may be of any shape desired but it is preferably made substantially square or polygonal and has rounded corners 5. The top 6 connected to the tub slopes towards 60 the center of the machine and provides a drain therefor. A suitable cover 7 is hinged to the top as shown in Fig. 2.

A pipe 8 connects with the L 9 integrally formed on the plate 10 bolted to the bottom of the tub and provides a passage to the interior of the tub to drain the same. A suitable valve 11 is arranged on the outer end of the pipe 8 to open and close the passage as 65 required.

Integrally attached to the bottom of the tub and at three corners thereof are tubular members 12 in which the tapering ends 13 of the frame legs 14 are received. A lug 15 integrally formed on the remaining corner of the tub carries a casing 16 and secured to the cover 17 which is bolted to the gear casing 18. Integrally formed on the bottom of the gear casing is a hollow member 19 into which the stub leg 20 of the frame engages. This leg 20 has a tapered end 21 the same 70 as the ends 13 of the legs 14.

The cover 17 has a vertical hollow member 22 integrally formed thereon which supports a standard 23 which supports the 75 wringer and houses its driving mechanism. A boss 24 formed on the side of the tub near the top receives the bolts 25 passing through a plate 26 secured to the standard and rigidly holds the standard in fixed position.

The frame 2 has a four-way T 27, Fig. 2, which receives a pipe 28 in each of two sides thereof. This T has side branches 29 and 30, the branch 29 being suitably arranged to receive the pipe 28 such as having a screw thread in the inside thereof and the branch 30 being split as at 31 to receive the end of the pipe 28 which may be screwed or otherwise fastened in an adjacent T. The ends 80 of the pipe in the split branches 30 are se- 85

surely fastened therein by a set screw 32 passing through alined holes formed in the lugs 33 which are integrally formed on the branch on each side of the split 31. A leg 14 of the frame 2 fits in the top of the T and a castor 34 is inserted in the bottom. As the hollow member 19 is spaced from the tub and not in the same relative position as the tubular member 12 a member 35 is provided of different construction from the four-way T 27 above described. This member 35 has a vertical body portion 36 to which a Y is integrally connected. This Y has a neck or stem 37 to which branches 38 and 38' are integrally connected at right angles to each other. The neck 37 being of sufficient length to bring the branches in alinement with the branches 29 and 30 of the T 27. By connecting the T's 27 to the member 35 the frame 2 is completely assembled as clearly shown in Figs. 1 and 2. It is understood of course that the stub leg 20 is mounted in the top of the body 36 of the member 35, and a castor 34 is mounted in the lower end thereof in the same manner as the legs 14 and castors 34 are arranged in the T 27.

In the ordinary type of frames for supporting washing machines only seventy five to eighty machines can be loaded in the normal cars while by providing a frame which can be "knocked down" or taken apart as the frame constituting part of this invention it is possible to load a hundred to a hundred and ten machines and even more in some cars. The cost of transporting is thereby considerably reduced and less handling is required.

Integrally formed on the bottom of the tub is a downwardly disposed lug 39 to which the motor 4 is secured. The motor has a bifurcated member 39' attached thereto which cooperates with the lug 39. A bolt 40 passing through the alined holes in the lug and bifurcated member hold the motor in fixed position. This allows the motor 4 to have a flexible or pivotal connection with the tub and it can be easily centered as regards its connecting driving mechanism. This construction is clearly shown in Figs. 5 and 7.

A worm 40 receives its motion from the motor shaft 41 of the motor 4 through a flexible coupling 42 which is arranged in the casing 18 and connects with a worm gear 43 loosely mounted on the vertical shaft 44. The worm gear 43 has a gear 45 rigid therewith which drives a spur gear 46 mounted on the wringer drive 47. The vertical shaft 44 has a squared portion 48 upon which is mounted a clutch member 49. The clutch member 49 has teeth 50 which are adapted to cooperate with projections 51 on the worm gear 43. A link 52 pivotally mounted in the casing 17 has a tooth 53 which is adapted to be received in the annular recess 54 formed in the clutch member 49. The outward end of the link 52 has a slot 55 formed therein which is adapted to

receive the hooked end 56 of the clutch rod 57. The clutch rod 57 has the upper end thereof mounted on the casing 58 integrally formed on the flange journal 59 of the standard 23. The lower end of this rod extends through a lug 60 which acts as a stop. A spring 61 is disposed between the bottom of the cover and the top of the knobbed end 62 and urges the clutch rod downward for keeping the clutch out of engagement. A handle 63 is formed on the end 62 to operate the rod 57.

A bayonet slot 64 formed in the side of the casing 58 is adapted to receive the lug or pin 65 formed on the clutch rod 57. When it is desired to throw the clutch into engagement the handle is pulled upward and given a partial turn so that the pin 65 is engaged and locked in the slot 64 as clearly shown in Fig. 9. By raising the clutch rod 57 the outer end of the link 52 is raised thereby lowering the clutch member 53 into engagement. It being understood of course that the wringer drive 47 is always rotating within the standard 23 when the motor is running.

Connected to the upper end of the shaft 44 and held in relative position by the boss 66 formed on the cover 17 is a crank arm 67. A shaft 68 which drives the impeller 69 and its cooperating vanes 70, has a crank arm 71 pivotally mounted on the lower end thereof. A rod 72 connects the crank arms 67 and 71 by means of pins 73 and 74 which are housed in suitable bushings 75 and 76.

By this arrangement, when the motor is running, the worm 40 causes the worm gear 43 which is loosely mounted on the shaft to rotate. When the clutch 49 is mounted on the squared portion 48 of the shaft 44, is in engagement as shown in Fig. 3 the shaft 44 will rotate, and cause the crank arm 67 to rotate with the shaft. The rod 72 being pivotally connected to the crank arm 67 will rotate at this end in a small circle thereby causing the opposite end of the rod to reciprocate. The crank arm 71 is rigidly mounted on the shaft 68 and pivotally connected to the rod 72 will therefore oscillate back and forth in an arc.

The wringer 3 has a horizontal drive shaft 77, Fig. 3, which is mounted in suitable bearings 78 arranged in the casing 79 and this drive shaft 77 has a square intermediate portion 80 on which a clutch member 81 having teeth 82 and 83 is mounted. Bevel gears 84 and 85 loosely mounted on the shaft 77 are constantly operated by a bevel gear 86 attached to the stub shaft 87. A clutch member 88 mounted on the lower end of the stub shaft 87 is adapted to cooperate with a clutch member 89 mounted on a wringer drive 47.

This arrangement provides a detachable connection or slip joint. The clutch member 89 is in the form of a sleeve and is disposed with a portion of the shaft 47 extended thereinto for a short distance. This portion of the shaft 47 is pinned in the sleeve. In the

portion of the sleeve extending beyond the end of the shaft 47 axially extending diametrically opposite slots are formed into which pins on the clutch member 88 extend 5 when the clutch member 88 is disposed in the sleeve of the clutch member 89.

Whenever the wringer is attached to the tub this stub shaft, and the motor running, the wringer shaft 47 rotates, thereby causing 10 the stub shaft 87 to rotate with it and causing the bevel gear 86 to rotate likewise. A short shaft 90 mounted in the wringer casing 79 is held in relative vertical position by a set screw 90' engaging an annular groove 90" formed in the shaft. A projection 91 formed 15 on the shaft 90 cooperates with a recess 92 formed in the clutch member 81. A handle 93 attached to the stub shaft 90 is adapted to operate the same.

20 When the handle is in the position shown as Fig. 3 it will be seen that the teeth 82 and 83 on the clutch member 81 are not in engagement with the bevel gears 84 or 85 and therefore the horizontal wringer shaft 77 is idle. 25 By moving the handle 93 in one direction the teeth on one side of the clutch member will engage the teeth in one of the bevel gears and cause the wringer rollers 94 to rotate it, being understood, of course, that suitable connection is made between the drive shaft 77 and 30 the wringer rollers 94, so that the rollers will rotate in opposite directions.

By moving the handle 93 in an opposite direction the teeth on the other bevel gear 35 will engage the teeth on the other side of the clutch member and cause the wringer rollers to reverse their movement. By shifting the handle midway between its full movement neither of the bevel gears will be locked in 40 driving position, and this position is termed neutral. A suitable lug or designating device mounted on top of the casing 79 may be provided to designate the neutral position, and movement of the lever either side of the 45 neutral position will cause the wringer to operate in the direction required.

An annular flange 94 integrally formed on the wringer casing 79 is adapted to rest on the top of the flanged journal 59 and support 50 the wringer and its cooperating mechanism. A lever 95 pivotally mounted between two lugs 96 integrally formed on the wringer casing 79 and supported thereby, engages a slot 97 formed in the flange 94. 55 This handle has a lug 98 formed on the bottom thereof of substantially the same thickness as the outer edge of the flange 94 and is of sufficient length to allow the same to enter and lock into both the slot 97 and a slot 99 formed in the top of the flange journal 59. A spring 100 interposed between the upper end of the lever 95 and the back of the casing 79, and held in relative position thereto, by any suitable means, causes 60 the lug 98 to engage the slot 97 in the flanges

94, and when the wringer is in position as shown in Fig. 1 the lug 98 engages both the slots 97 and 99 in the flanges 94 and 59 respectively. When it is desired that the wringer be shifted in any position, pressure 70 on the upper end of the lever 95 causes the lug 98 to recede from the slots and the wringer may be revolved about the shaft 87. By releasing the handle the spring 100 causes the lug to engage and lock into the slot 97 75 and into one of the slots 99 in the flange journal, thereby holding the wringer in fixed position.

The wringer is so constructed, as will be noted from the foregoing description, that 80 when the same is not in use it may be easily removed from the standard and set in any suitable place.

A washing machine has been devised which 85 has a unique, practical and positive form of drive, and includes many new and novel features heretofore unknown in the washing machine art.

Changes in construction and arrangement 90 of the parts may be made without departing from the scope or spirit of the invention, or sacrificing any of the advantages thereof and the right is hereby reserved to make such changes as fairly fall within the scope of the following claim.

I claim:

A driving mechanism for a combined washer and wringer including an impeller shaft, a vertical shaft, a crank on the impeller shaft and a crank on the vertical shaft, 100 a link connecting said cranks for imparting an oscillating movement to the impeller shaft, a worm gear loosely mounted on the vertical shaft, a worm drive for operating said gear, a wringer drive gear secured to 105 said worm gear and meshed with a gear on the wringer drive shaft, a clutch comprising a member rigid with said worm gear and a member movably mounted on the vertical shaft between the worm gear and the 110 crank, a pivotally mounted operating arm having an end portion connected to the movable member of said clutch, and means connected to the other end of said pivotally mounted arm for imparting movement thereto for controlling operation of said vertical shaft and said impeller shaft from said worm gear.

OTTO E. SZEKELY.
